Primary Examiner — T Chase Nelson*Assistant Examiner* — Sydney Margaret Parsley(74) *Attorney, Agent, or Firm* — Brooks Kushman P.C.(57) **CLAIM**

The ornamental design for a collapsible shelter, as shown and described.

DESCRIPTION

FIG. 1 is a front perspective view of a collapsible shelter; FIG. 2 is a lower perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is an upper perspective view of the collapsible shelter of FIG. 1 after collapse.

The broken lines in FIGS. 1–8 represent an exemplary canopy under which the structures of FIGS. 1–8 reside and form no part of the claimed design. The circular elements in broken lines found on the scissor linkage arms, and on the cross-like connectors in FIGS. 1–6 and 9 are disclaimed and form no part of the claimed design.
